UNITED STATES PATENT OFFICE

JOSEPH G. SOLA, OF CHICAGO, ILLINOIS, ASSIGNOR TO SOLA CORPORATION, OF CHICAGO, ILLINOIS, A CORPORATION OF ILLINOIS

VOLTAGE COMPENSATOR

Application filed August 7, 1930. Serial No. 473,692.

My invention relates to voltage compensators for alternating currents and it has for its object the provision of a new and improved form and arrangement of automatically operating parts adapted when connected to an alternating current line to deliver a current at reduced voltage when the voltage on the line becomes too high and to deliver a current at increased voltage when the voltage on the line becomes too low. It is one of the objects of my invention to provide an improved construction of simple form, comprising a coil mounted upon a core which provides a return path, and comprising auxiliary core means providing a shunt return path of comparatively much greater reluctance than that of said principal return path, with means adapted as said principal return path approaches saturation by reason of an increased voltage through said coil to have increasing effect to oppose the current through said coil and thus to cut down the voltage of the current delivered.

It is one of the objects of my invention, particularly in cases where it is desired to operate an electrical device at the normal voltage delivered by the alternating current line, to provide an improved arrangement for first stepping up the voltage, providing thus for the contingency that the line voltage may be too low, and then cutting down such increased voltage to the necessary extent, with the arrangement such that when the voltage on the line is low the effect of the voltage reduction means shall not be so great as that of the voltage increasing means, and that when the voltage on the line is high the effect of the voltage reduction means shall be materially greater than that of the voltage increasing means.

It is one of the objects of my invention to provide an arrangement by which the gradual increase in the degree of saturation of a principal return path as the voltage increases may be utilized for correspondingly increasing the effect of the means provided for cutting down the voltage of the current as delivered to the load apparatus.

It is another object of my invention to improve devices of this type in sundry details

hereinafter pointed out. The preferred means by which I have accomplished my several objects are illustrated in the drawing and are hereinafter specifically described. That which I believe to be new and desire 55 to cover by Letters Patent is set forth in the claims.

In the drawing:—

Fig. 1 is a diagrammatic view showing the preferred form of my improved voltage compensator, with certain parts broken away for 60 clearness of illustration.

Figs. 2 and 3 are face views of the two cooperating parts respectively of the core of my improved construction as shown in Fig. 65 1; and

Fig. 4 is a face view of a modified form of core means.

Referring now to Figs. 1, 2 and 3, in which corresponding parts are indicated by the same reference characters, it will be seen that my apparatus comprises transformer means in the form of an autoformer made up of a primary coil 10 and a secondary including the 70 coil 10 and an auxiliary coil portion 11, said coils being provided with core means as hereafter described. The primary coil 10 is connected between the leads 12 and 13 of an alternating current line. A third coil 14 is connected in series with the secondary coil of the transformer in such relation as to oppose such secondary coil, being wound in the opposite direction about the core means. Leads 15 and 16 are connected at opposite ends of the connected coils for delivery of the load current from the device.

The core of my improved apparatus is all of laminated form, the several plates of which are held together by means of clamping bars 17 which in turn are connected to each other by means of bolts 18. One of the members of the complete core means is in the form of a rectangular piece 19 having inwardly extending arms 20 which are in spaced relation to each other so as to receive snugly between them a core bar comprising a wide portion 21 at one end and a comparatively narrow portion 22 at the opposite end. In the construction shown the plates making up the core bar 21—22 are connected together by means of a 95 100

rivet 23. The bar comprising the portions 21 and 22 is rounded at one end so as to have a snug fit within a groove 24 in the inner face of one of the side bars of the rectangular core part 19. At its opposite end, the core bar 21—22 is separated from the side of the rectangular part 19 by an air gap as shown at 25.

In the construction shown, the arms 20 of 10 the core means are made of such size as to cause them to be substantially saturated when the voltage of the current passing through the coil 10 under normal load conditions is approximately normal. Under such conditions with a current of normal voltage flowing through the coil 10, the major portion of the magnetic lines of force about the coil 10 will pass through the return path comprising the arms 20 and the rectangular core part 15 20 19, since the air gap at 25 causes the reluctance of the auxiliary return path through the bar portion 22 to be so much greater than the reluctance through the principal return path comprising the arms 20 that there will be a 25 very small proportion of the lines of force passing through such auxiliary return path. As the voltage through the primary coil 10 increases beyond the normal so as to cause the 30 normal return path to approach closely to saturation, the proportion of lines of force passing through the auxiliary return path comprising the bar portion 22 and the air gap 25 increases rapidly.

With the voltage through the primary coil 35 10 at normal, the voltage through the secondary coil comprising the coil parts 10 and 11 will be found to be very materially higher, the voltage between the leads 15 and 16, however, will be considerably lower on account of the inductance drop through the coil 14 and the counter-voltage set up in said coil 40 14 by the influence of the field in the auxiliary return path comprising the core bar portion 22. The strength of this counter-voltage 45 15 age is directly proportional to the strength of the field in the auxiliary return path, which in turn is controlled by the reluctance of such auxiliary return path as compared with the reluctance of the principal return path. The size of the air gap 25, by which the 50 55 reluctance of the auxiliary return path is controlled, is designed to be such that, when there is a normal voltage in the coil 10, the increase in voltage in the secondary coil 10—11 brought about by the use of the transformer will be approximately equalled and offset so far as the voltage between the leads 15 and 16 is concerned by the decrease in the voltage between said leads due to the inductance drop 60 through the coil 14 and the counter-voltage through said coil. Thus when there is a normal voltage between the line leads 12 and 13 there will be approximately the same voltage between the load leads 15 and 16.

With the parts arranged for operation as

above described, effective compensation will be brought about when the voltage through the coil 10 departs from the normal. When the voltage through the coil 10 is increased to a point above the normal voltage, the strength of the field in the auxiliary return path comprising the core bar portion 22 is at the same time increased rapidly, since a great proportion of the magnetic lines of force added by reason of such increase of voltage 70 pass through such auxiliary return path by reason of the close approach to saturation in the principal return path. This serves very materially to increase the counter-voltage in the coil 14, with the result that a large proportion of the increase in the voltage through the coil 10 is offset and the increase in voltage 75 between the leads 15 and 16 is caused to be very materially less than the increase through the coil 10.

When the voltage through the coil 10 falls to a point below the normal, the strength of the field in the auxiliary return path comprising the core bar portion 22 is decreased, and at the same time the degree of saturation in the principal return path is lowered. Under such conditions, the amount of the decrease in the strength of this field for a given drop in voltage is much smaller than the decrease for a similar drop in voltage when the 90 degree of saturation in the principal return path is comparatively higher. When the voltage through the coil 10 drops below normal, the counter-voltage through the coil 14 serves to reduce the voltage between the leads 100 15 and 16, but not sufficiently to cause such counter-voltage and the inductance drop through the coil 14 together to balance the increase in voltage in the transformer. It follows, accordingly, that when there is such a drop in voltage in the coil 10 below normal at the same time the voltage between the leads 15 and 16 also drops below normal, but that the drop between the leads 15 and 16 is very 105 materially less than the drop through the coil 10.

It is thus seen that my improved apparatus serves to deliver between the leads 15 and 16 a current of a higher voltage than that of the current flowing through the coil 10 when the voltage in such coil 10 falls below a predetermined normal and to deliver between said leads 15 and 16 a current of a lower voltage than that of the current through the coil 10 when the voltage in such coil 10 rises above 110 such predetermined normal.

In practicing my invention I have built a device in accordance with the showing of Fig. 1 for use in connection with an alternating current line having a normal voltage of 110 volts, such device being designed to deliver a normal load current of the same voltage. This device has been found to provide approximately a fifty per cent correction for variations in line voltage. That is to 125 130

say, when the voltage through the coil 10 has fallen to 100 volts the voltage delivered through the leads 15 and 16 has been found to be approximately 105 volts, and when the 5 voltage through the coil 10 has risen to 120 volts the voltage through said leads 15 and 16 has been found to be approximately 115 volts.

In this machine so built in accordance with the showing of Fig. 1 and operating as above 10 set forth, the primary coil 10 has 195 turns, the coil portion 11 has 105 turns, giving the secondary coil complete 300 turns, and the coil 14 has 300 turns. The core bars 20 are of such width as to cause a close approach 15 to saturation therein when the line voltage is at the normal 110 volts. The air gap 25 is of such size as to cause the inductance drop through the coil 14 and the counter-voltage in said coil substantially to balance the increase 20 in voltage produced by the transformer, whereby the voltage between the leads 15 and 16 is substantially 110 volts when the line voltage is 110 volts.

In the arrangement shown in Fig. 4, the 25 core comprises a bar 26, with arms 27 extending at right angles thereto, and an arm 28 extending in continuation of the bar 26. Upon the outer ends of the arms 27, there are bars 29 parallel with the bar 26, the parts 30 26, 27, 28 and 29 being formed integrally with each other. A separately formed bar 30 is provided across the ends of the bars 29 and 26, and another separately formed bar 21 is provided at the opposite ends of the bars 35 29 in spaced relation to the bar 28. In this arrangement, the principal return path comprises the parts 26, 27, 29 and 30, while the auxiliary return path comprises the parts 28, 31 and 29. The coils 10 and 11 are, of course, to be mounted on the bar 26, and the coil 14 on the arm 28, the arrangement being such that the operation and effect are the same as those above described in connection 40 with the construction shown in Fig. 1.

45 The description of the construction and operation above applies to the preferred form of my improved device, but the invention is not in any way limited to some of the features as there set forth. For example, while 50 I prefer to proportion the arms 20 so that they shall have a close approach to saturation when the voltage in the coil 10 approaches the normal, it will be understood that my invention broadly is not limited thereto, it being evident that a device arranged with a differently selected point of saturation would have a field of usefulness. In the same way, 55 my invention broadly is not to be limited with respect to the size of the air gap 25 whereby the counter-voltage and the inductance drop are made to balance or offset the transformer increase in voltage when the line voltage is at normal strength. It might well be that the designer would prefer to have this balanced 60 condition take place when the line voltage is

either above or below such normal strength. In general, my invention is not to be limited to the form as shown and described except so far as the claims are so limited by the prior art.

70 I claim—

1. In a voltage compensator, the combination of a core, primary and secondary coils mounted on said core in transformer relationship and arranged so that the voltage normally impressed on the secondary has a constant ratio to the voltage in the primary, a portion of said core means being of such reduced size as compared with the remaining portions that upon the passage of the normal current of normal voltage through the primary coil said reduced portion of the core shall have a close approach to saturation, auxiliary core means providing a shunt return path about said core portion of reduced size for carrying a portion of the flux threading said primary and secondary coils, and auxiliary coil means mounted on said auxiliary core and connected in series with said secondary coil in opposition thereto adapted by the action thereon of the magnetic flux through said auxiliary core to cut down the voltage through the connected secondary and auxiliary coils to a point well below the voltage normally impressed on said secondary 85

90

2. In a voltage compensator, the combination of a core providing a closed magnetic circuit and comprising a portion of predetermined cross sectional size and the remaining portion of greater cross sectional size, primary and secondary coil means mounted in transformer relationship to each other on said core portion of greater cross sectional size adapted upon the passage of the predetermined normal current of normal voltage through the primary coil means to produce substantial saturation in said reduced portion of the core, auxiliary core means 100 adjacent to said core portion of reduced size 105 providing a shunt return path thereabout, and auxiliary coil means mounted on said auxiliary core means and connected in series with said secondary coil in opposition thereto. 110

115

3. In a voltage compensator, the combination of a core providing a closed magnetic circuit and comprising a portion of predetermined cross sectional size and the remaining portion of greater cross sectional size, primary and secondary coil means mounted in transformer relationship to each other on said core portion of greater cross sectional size adapted upon the passage of the predetermined normal current of normal voltage 120 through the primary coil means to produce substantial saturation in said reduced portion of the core, auxiliary core means providing a shunt return path about said core portion of reduced size, and auxiliary coil means 125

- mounted on said auxiliary core means in substantially non-inductive relationship to the magnetic flux passing through said core portion of reduced size and connected in series with said secondary coil means in opposition thereto.
4. In a voltage compensator, the combination of a core providing a closed magnetic circuit and comprising a portion of predetermined cross sectional size and the remaining portion of greater cross sectional size, primary and secondary coil means mounted in transformer relationship to each other on said core portion of greater cross sectional size adapted upon the passage of the predetermined normal current of normal voltage through the primary coil means to produce substantial saturation in said reduced portion of the core, auxiliary core means providing a shunt return path about said core portion of reduced size, and auxiliary means mounted on said auxiliary core means in substantially axial alignment with said primary coil and connected in series with said secondary coil in opposition thereto.
5. In a voltage compensator, the combination of a core comprising a straight bar and a return path portion cooperating to provide a closed magnetic circuit, primary and secondary coil means mounted in transformer relationship on said straight bar adapted upon the passage of the normal current of normal voltage through the primary coil means to produce substantial saturation in at least a part of the return path portion of said core, auxiliary core means providing a shunt return path about said part of the first named return path in which substantial saturation is produced and arranged to have a comparatively much higher normal reluctance than that of the first named return path means, and auxiliary coil means mounted on said auxiliary core means and connected in series with said secondary coil in opposition thereto.
6. In a voltage compensator, the combination of a core comprising a straight bar and a return path portion connecting an intermediate part and one end of said straight bar in a closed magnetic circuit, primary and secondary coil means mounted in transformer relationship on said straight bar adapted upon passage of the normal current of normal voltage through the primary coil means to produce substantial saturation in at least a part of the return path portion of said core, auxiliary core means providing an auxiliary return path from the opposite end of said straight bar to said first named return path portion and arranged in parallel shunt relation to said portion of the first named return path in which substantial saturation is produced, and an auxiliary coil mounted on said opposite end portion of said straight core bar beyond said first named return path portion and connected in series with said secondary coil means in opposition thereto.
